AUTOMOBILE WHEEL

Paul J. Mochel, Studio City, Calif., assignor to
Appliance Plating Co., Inc.

Filed Sept. 10, 1971, Ser. No. 179,611

Term of patent 14 years

Int. Cl. D12—16

U.S. Cl. D12—205

FIG. 1 is a side elevation view of the wheel;
FIG. 2 is an end elevation view of the wheel;
FIG. 3 is a side elevation view of the wheel taken
from the side opposite to that of FIG. 1; and
FIG. 4 is a cross sectional view of the wheel taken
along the plane indicated by 4—4 in FIG. 1.

I claim:

The ornamental design for an automobile wheel, as
shown.
